UNITED STATES PATENT OFFICE.

WILLIAM F. PAGEL, OF SYCAMORE, ILLINOIS.

PLUMBER'S TORCH.

Application filed November 20, 1922. Serial No. 602,020.

To all whom it may concern:

Be it known that I, WILLIAM F. PAGEL, a citizen of the United States, and resident of Sycamore, in the county of De Kalb and State of Illinois, have invented certain new and useful Improvements in a Plumber's Torch, of which the following is a specification.

My invention relates to an improvement in so-called plumbers' torches and has special reference to an improvement in the fuel feed means of such torches.

The object of my invention is to transmit sufficient heat from the burner to the fuel as it is fed from the reservoir to the burner to prevent any but vaporized or gasified fuel being projected into the burner tube through the fuel feed orifice even when lower grade fuel such as kerosene is used.

A further object of my invention is to prevent the surging or intermittent ejection of fuel in liquid form through the exit opening and also to prevent any return of hot gases or fuel into the reservoir through the fuel feed passages.

My invention will be more readily understood by reference to the accompanying drawings forming part of this specification, and in which:

Figure 1 is a fragmentary side elevation of a plumber's torch shown partly in section and made in accordance with my invention; and

Figure 2 is a similar sectional view of the burner tube and associated feed passages showing a slight modification of my invention.

In said drawings, 1 is a fuel reservoir similar to the usual form of reservoirs of plumbers' torches. Upon the top of the reservoir is a removable member 2 carrying a handle 3 and a pump 4. Suitable means are provided for feeding the fuel from the reservoir 1 into the member 2 and I provide a fuel delivery pipe 5 extending from the member 2 and curved upwardly, and upon the upper end of which is secured a burner member 6. The burner 6 comprises a burner tube 7 arranged substantially horizontally and below which is provided a fuel feed passage 8 connecting at one end with a vertical opening 9 in the lower part of the burner and in the lower end of which passage the upper end of the tube 7 is sealed. The feed passage 8 connects with suitable passages in a member 10 carrying suitable adjustable

valves 11 and 12 and by which the fuel is directed through a nozzle 13 axially of the burner tube 7. The burner 6 is usually made of brass.

In use, air pressure is applied to the reservoir 1 above the liquid fuel therein by means of the pump 4, and the fuel is forced up through the delivery pipe 5 to the feed passage 8 but I do not desire to permit the fuel in liquid form to enter the passage 8 for the reason that if it does, it will be ejected in liquid form through the nozzle 13 as enough heat is not transmitted to the fuel through the burner casting while the fuel is flowing through the passage 8 to vaporize the present day low grade fuel.

To prevent the fuel in liquid form entering the passage 8, I provide a vaporizer in the form of a tapered plug or projection 14 arranged centrally within the passage 9 and having its smaller end 15 projecting down into the upper end of the said feed tube 5. The base of the cone is at the upper end and is seated upon a shoulder 16 in the burner casting. The upper part 17 of this member is cylindrical and externally threaded to fit tightly within a threaded opening 18 provided in the lower wall of the burner casting. The extreme upper end 19 of this member extends into the burner tube 7 and being arranged substantially at the middle point thereof is projected into the path of the flame in the burner tube and in position to take up heat therefrom.

The burner tube 7 is provided with a circumferential enlargement 7' at its middle portion which forms more or less of a chamber defined at its ends by circumferential shoulders 7", and the upper end 19 of the vaporizer plug extends into this chamber substantially midway between said shoulders. The chamber 7' permits an expansion of the burning gases which serves to retard somewhat their progress through the burner tube and assists in the mixing of the fuel and air and the production of a high temperature at this point to which the upper end of the plug is exposed on account of it projecting into this chamber.

I make the vaporizing plug of suitable metal such as copper, or an alloy of aluminum and copper, which is highly conductive of heat. The action of this member is as follows. The liquid rising within the tube 5, first comes into contact with the smaller end 15 of the heating plug, and this

plug being hot the contact of the fuel with the lower end thereof tends to immediately vaporize the fuel. If the fuel flows fast enough to cool the lower end or tip of the plug it rises into contact with more and more of same whereby more and more heat is transmitted to the fuel. The peculiar shape of the plug, that is, having a broad base and a small point serves to proportion the transmission of heat to the rising fluid fuel as the further the fuel rises the larger its contact with the heating projection and consequently more heat is transmitted to the fuel.

15 As no fuel in liquid form is allowed to enter the passage 8 there is no tendency to drive hot fuel either in liquid or gaseous form back into the reservoir as the gasified fuel has free outlet through the nozzle 13 and immediately any pressure is produced the rising fuel is driven back out of contact with the vaporizing plug and when this occurs the pressure does not increase further. The projecting end 19 of the vaporizing plug 25 15 serves as a baffle against which the flame is projected. In Figure 2, I have shown a form of vaporizing plug which is provided with a similar coned lower end 15 but instead of projecting through into the burner tube the upper end 20 in this case is threaded into a socket opening 21 in the burner casting and the lower wall of the burner tube is provided with an inwardly projecting baffle wall 22 which surrounds the socket 21. 30 35 For many of the higher grades of fuels used in such torches the form shown in Figure 2 is preferable for the reason that there is no opening made through the lower wall of the burner tube but for the lower 40 45 grades of fuel such as those known as the "kerosenes", the form shown in Figure 1 is preferable.

As many modifications of my invention will readily suggest themselves to one skilled in the art, I do not limit or confine my invention to the specific details of construction herein shown and described.

I claim:

1. In a torch of the kind described, a 50 burner tube, a reservoir from which fuel is adapted to be fed to the burner by pressure, a passage through which the fuel is fed, a member of high heat-conductive material 55 metallically connected to the wall of the burner tube and having an end projecting into said passage and arranged to cause the fuel as it flows to the burner to first contact with the free end of said member.

2. In a torch of the kind described, a 60 burner tube, a reservoir from which fuel is adapted to be fed to the burner by pressure, a passage through which the fuel rises to the burner, a member of high heat-conductive material rigidly secured to in free heat 65 conducting relation the wall of the burner

and projecting down into said passage and adapted to conduct heat to the fuel as it rises in said passage to flow to the burner.

3. In a torch of the kind described, a 70 burner tube, a reservoir from which fuel is adapted to be fed to the burner by pressure, a passage through which the fuel rises to the burner, a tapered member of high heat conductivity metallically and rigidly mounted at its base in the wall of the burner and having its free smaller end projecting downwardly into said passage and adapted to conduct heat to the fuel as it rises in said passage to flow to the burner.

4. In a torch of the kind described, a 80 burner tube, a reservoir from which fuel is adapted to be fed to the burner by pressure, a passage through which the fuel rises to the burner, a metallic member rigidly mounted in the wall of the burner, for receiving heat from the wall of the burner tube and conducting it to the fuel as the fuel rises through said passage to flow to the burner.

5. In a torch of the kind described, a 90 burner tube, a reservoir from which fuel is adapted to be fed to the burner by pressure, a passage through which the fuel rises from the reservoir to the burner, a baffle in the burner tube between its ends, a metallic 95 member rigidly mounted in the wall of the burner adjacent to said baffle for absorbing heat therefrom, the said member being tapered and its free smaller end extending down into the passage through which the fuel rises to the burner and adapted to heat the fuel as it flows through said passage.

6. In a torch of the kind described, a 100 burner tube, a reservoir from which fuel is adapted to be fed to the burner by pressure, a passage through which the fuel rises to the burner, a member of high heat-conductive material mounted in the wall of the burner, the base of the member projecting 110 into the burner tube and forming a baffle adapted to project into the flame in the burner tube and absorb heat therefrom, the member being sealed into the wall of the burner tube and having a tapered end projecting down into said passage to heat the fuel as it flows through the passage to the burner.

7. In a liquid fuel burning device of the kind described, having a passage through which liquid fuel rises on its way to the burner, a tapered heat conducting projection extending downwardly and freely into said passage, the projection at its larger end 120 metallically connected to the wall of the burner for receiving heat therefrom.

Signed at Chicago, Illinois, this 7th day of November, 1922.

WILLIAM F. PAGEL.
